(57) **CLAIM**

The ornamental design for a reagent consumable tube, as shown and described.

DESCRIPTION

FIG. 1 is a top perspective view illustrating a reagent consumable tube;

FIG. 2 is a bottom perspective view of the reagent consumable tube;

FIG. 3 is a front elevation view of the reagent consumable tube;

FIG. 4 is a rear elevation view of the reagent consumable tube;

FIG. 5 is a right side elevation view of the reagent consumable tube;

FIG. 6 is a left side elevation view of the reagent consumable tube;

FIG. 7 is a top plan view of the reagent consumable tube;

FIG. 8 is a bottom plan view of the reagent consumable tube;

FIG. 9 is a cross-sectional elevation view taken along line 9-9 in FIG. 7; and,

FIG. 10 is a cross-sectional perspective view taken along line 10-10 in FIG. 7.

The short-dash short-dash long-dash broken line arrows in FIG. 7 represent the cross section reference arrows and form no part of the claim thereof.

1 Claim, 9 Drawing Sheets
